DOOR

Joseph Sylvan, Berkley, Mich.

Application March 27, 1952, Serial No. 278,873

7 Claims. (Cl. 20—35)

This invention relates to a metal clad door and particularly to a door comprising a wood frame having metal sheets secured to opposite sides thereof and metal channels embracing the outer margins of the door overlapping the metal sheets.

Heretofore, metal clad doors of this type have been fabricated according to the disclosure of my Patent No. 2,582,467. These doors were provided primarily as storm doors and consisted of a wood frame covered with sheet material.

Such patented door had a wood frame composed of two upright wood stiles connected at the top by a wood header and elsewhere connected by wood cross frame members spaced vertically from the header. The header, the two stiles, and one wood cross frame member defined a window opening. Metal sheets were secured to opposite sides of this frame completely covering the wood frame and secured thereto by nails or the like. Sheet metal channels embraced the outer margins of the door and gripingly engaged the metal sheets.

It has been found under certain conditions that certain portions of the wood frame tended to shrink following the fabrication of the door. As an example, a stile member alongside the window opening might shrink. Inasmuch as the metal plate was secured adjacent to both margins of the stile member by a row of nails, such shrinking might result in buckling of the metal plate.

This invention relates to a door which is so constructed that shrinking or contracting of portions of the wood frame member will not result in buckling of the overlying metal sheets. The wood frame is so constructed, and the metal sheets so secured thereto that shrinking of the wood frame underneath the metal sheets may occur without any resulting undesirable buckling of the sheets.

A further meritorious feature of the door of this invention is that the construction is such that any change in dimension of a portion of the wood frame within the metal sheathing will not result in such undue pressure being put upon the fastening means as to loosen such means which attaches the metal sheets to the frame. Whether such change in dimension is one of contraction or expansion, the instant construction can be accommodated to take care of it without any loosening of the fastening means or buckling of the sheet material.

Other objects, advantages and meritorious features of the invention will more fully appear from the following specification, claims and accompanying drawings, wherein:

Fig. 1 is an elevation of a door embodying my invention with a portion of one metal sheet broken away to illustrate the wood frame;

Fig. 2 is a vertical sectional view taken on the line 2—2 of Fig. 1;

Fig. 3 is a vertical sectional view taken on the line 3—3 of Fig. 1 and being broken away and enlarged;

Fig. 4 is an elevation of a fragment of an upper corner of the door shown in Fig. 1 with part of the overlying metal sheet removed and with the wood frame partly broken away;

Fig. 5 is a view taken on the same sectional line as Fig. 2 but showing the shrinking of a portion of the wood frame between the overlying metal sheets;

Fig. 6 is a transverse sectional view taken on the line 6—6 of Fig. 1;

Fig. 7 is a transverse enlarged sectional view taken along line 7—7 of Fig. 1;

Fig. 8 is an elevation of a door of a slightly modified form as compared with the door of Fig. 1;

Fig. 9 is a transverse sectional view taken on the line 9—9 of Fig. 8.

Considering the door of Fig. 1, there is a wood frame which consists of a pair of upright wood stiles indicated at Figs. 1 and 6. These stiles are connected together at

2

the bottom by a cross frame member 12 (Figs. 1 and 3), and at the top by a cross frame member 14 (Figs. 2 and 4). The bottom cross frame member 12 and the top header 14 are secured by nails or the like 16 to the ends 5 of the stiles 10. A second cross frame member 16 is shown in Fig. 3 and this cross frame member connects the two stiles together just below the window opening. These three cross frame members 12, 14 and 16 and the two stiles 10 form a wood frame for the door.

10 A pair of metal plates 18 cover that portion of the door below the window opening and are secured to the cross frame members 12 and 16 and the stiles 10 by nails 20 or the like. A pair of metal plates 22 as shown in Figs. 1, 6 and 7, cover each of the two upright stiles 10 and are secured thereto by nails 24 or the like as shown in Figs. 6 and 7.

15 A pair of metal plates 26, as shown in Figs. 1, 2 and 5, cover the header 16 on opposite sides and are secured thereto by nails 28 or the like.

20 The door may be provided with suitable hinges 30 and a door latching arrangement 32, each of which has nothing to do with the invention.

25 Metal channels 34 extend along and over and embrace the outer margins of the door frame and overlap the metal sheets disposed on opposite sides thereon. One such channel 34 is shown as extending along over the top margin of the header 14 in Figs. 2 and 5. Another such channel 34 is shown as extending along over the bottom margin of the bottom cross member 12, as shown in Figs. 1 and 3. Two other such channels 34 are shown 30 extending along over the outer margins of the stiles in Figs. 1 and 6. The side walls of these channels gripingly engage the metal sheets. The side walls of these channels extend over and beyond the row of securing means or nails which secure the sheets to the wood frame, 35 all as shown in the several figures referred to hereinabove.

30 Furthermore, the metal sheets themselves are shown as terminating spaced inwardly of the outer margin of the wood frame whether along the outer margins of the stiles or along the top margin or the bottom margin of the frame. Generally, the above is all shown and described in a manner above heretofore referred to.

40 The wood frame of the instant construction however differs from that of the patent referred to. In the instant wood frame, each of the stiles 10 is shown as provided with or including a separate wood strip 38 which extends along the inner margin of the stile and may be secured thereto by connecting means such as nails 40. These nails 40 are driven through the strip into the main body of the wood stile, but the strip is separable to be moved relatively toward or away from the main body of the wood stile by partial withdrawal of the nails therefrom. Such a wood strip also is shown as extending along the header 14. Such strip is there indicated by the numeral 42 and the strip 42 is shown as secured to the inner margin of the header by the nails 44. Such strip is relatively shiftable with respect to the header toward or away therefrom by partial withdrawal of the nails from the main body of the header.

45 The lower margin of the header 14 is covered by a metal channel 48 which extends therealong embracing such lower margin as shown in Figs. 1, 2 and 5. This channel exhibits a downwardly opening header channel 50 adapted to receive the upper edge of a framed glass pane 52, as shown in Figs. 1, 2 and 5.

50 The opposed inner margins of the stiles are provided with metal channels 54 which extend therealong and embrace the same. These channels extend inwardly over the 55 nails 40 which connect the plates 22 to the strips 38. Each of these channels has an inwardly projecting lip 56 adapted to serve to hold the window pane in place. The cross frame member 16 has a metal channel 58 extending along over and embracing the upper margin and overlying the metal plates 18, as shown in Fig. 3. This metal channel is provided with an upright flange 60 which serves as an abutment for a framed window pane 54.

55 While kiln dried wood is used to fabricate the wood frames, such wood pieces are not always thoroughly dried. They may pick up moisture during shipping, storage or fabrication. When the metal plates are secured thereto,

as for example, the metal plates 26 are secured to the header 14, such plates will be secured along their upper margin by a row of nails extending along adjacent to the upper margin of the header. The lower margin of this header is formed by the separate strip 42 which is secured to the edge of the main body of the header by nails 44. The metal plates 26 are secured to this strip 42 along the lower margin of such plates by nails 58. If the header shrinks the metal plates being secured along their top margins to the main body of the header 16 and secured along their bottom margins to the separate strip 42 permit such shrinkage as the nails 44 to withdraw partially from the main body of the header. The wood frame is sufficiently protected by the metal sheathing as to substantially eliminate any accumulation of moisture which would produce expansion, but if the material were thoroughly dehydrated at the time of fabrication of the wood frame, and if there were any likelihood of moisture accumulation by the frame, the construction could be initially set up as shown in Fig. 5 and thereby expansion of the wood frame would be provided for.

In Figs. 8 and 9, a modified form of door is shown as compared with that of Fig. 1. In these Figures 8 and 9, two large window panes are shown. The intermediate cross frame member is omitted. The frame consists of the two stiles, a header and a bottom cross frame member. Metal plates are secured to opposite sides of the stiles and the opposite sides of the header and bottom cross frame member. The construction of the stiles with the separate wood strips is as shown in Figs. 6 and 7 heretofore described. The construction of the header is as shown in Figs. 2 and 5 hereinabove described. The construction of the bottom frame member which is here indicated as 12a is similar. This bottom frame member includes a separate strip 60 which extends along its inner or upper margin and is secured thereto by nails 62. This strip is separable with respect to the main body of the cross frame member 12a. Metal plates 64 are secured to opposite sides of this bottom frame member 12a by nails 66 which extend as a row along the bottom margin into the main body of the frame member 12a by nails 68 which extend as a row along the top margin and to the separate strip 60.

A metal channel 70 is shown as extending along and embracing the inner edge of this cross frame member 12a and provide a seat for the lower glass pane indicated by the letter L. The upper glass pane in this assembly is indicated by the letter U. This channel 70 has an upwardly projecting flange 72 as shown in Fig. 9.

The construction of Fig. 1 does not show any separate strips on the inner margins of the lower portions of the stiles 10 covered by the metal plates 18 and neither are any separate strips shown on the bottom cross frame member 12, or the intermediate cross frame member 16. This is due to the fact that the metal sheets 18 are not attached at two places to the same wood strip and are therefore free to expand or contract.

What I claim is:

1. A metal clad door having a wood frame provided with a pair of complementary wood stiles connected by vertically spaced cross frame members defining with the stiles a window opening, each stile including a separate marginal strip extending linearly along one upright margin of the main body of the stile and shiftably coupled therewith for shiftable movement toward and away from the main body of the stile, a pair of metal plates disposed on opposite sides of each stile and connected along one margin with the main body of the stile and connected along the opposite margin with the separate strip.

2. A metal clad door having a wood frame provided with a pair of complementary wood stiles connected by vertically spaced cross frame members defining with the stiles a window opening, each stile including a separate marginal strip extending linearly along one upright margin of the main body of the stile and secured thereto by connecting means extending through the strip into the edge of the main body of the stile, said strip being shiftable toward and away from the edge of the main body of the stile, a pair of metal plates disposed on opposite sides of each stile, said plates being secured to the stile along one margin by connecting means extending through the plates and into the main body of the stile and secured thereto along the opposite margin by connecting means extending through the plates and into the strip.

3. A metal clad door having a wood frame provided with a pair of complementary wood stiles connected by

vertically spaced cross frame members defining with the stiles a window opening, each stile including a separate marginal strip extending linearly along the inner margin thereof and connected therewith for shiftable movement toward and away from the main body of the stile, a pair of metal plates disposed on opposite sides of each stile, said plates connected with the stile by a row of connecting means extending through the plates into the main body of the stile disposed adjacent to the outer margin thereof, and by a second row of connecting means extending through the plates and into the strip adjacent to the inner margin of the stile.

5. A metal clad door having a wood frame member, metal plates disposed on opposite sides of said frame member and secured thereto along one margin by connecting means extending through the plates and into the wood frame member, said wood frame member provided with a separate wood strip extending along its opposite margin and connected therewith for shiftable movement toward and away from the edge of the frame member, said plates secured to the strip by connecting means extending through the plates and into the strip.

10. A metal clad door having a wood frame provided with a pair of complementary wood stiles connected at the top by a wood header and connected spaced below the header by a wood cross frame member defining with the stiles and the header a window opening, a pair of metal plates disposed on opposite sides of each of said stiles and secured thereto along the outer margins of the plates by a row of connecting means extending through the plates and into the stiles, each of said stiles including a marginal strip extending along the inner margin of the stile and secured thereto by connecting means extending through the strip and into the stile, said strip being shiftable toward and away from the main body of the stile, a row of connecting means extending through the plates into said strip, a metal channel extending along the outer margin of each stile embracing said margin of the stile and having side walls grippingly engaging the metal plates on opposite sides of the stile covering a row of connecting means extending along said margin of the stile.

15. A metal clad door having a wood frame provided with a pair of complementary wood stiles connected at the top by a wood header and connected spaced below the header by a wood cross frame member defining with the stiles and the header a window opening, a pair of metal plates disposed on opposite sides of each of said stiles and secured thereto along the outer margins of the plates by a row of connecting means extending through the plates and into the stiles, each of said plates terminating spaced from the outer margin of the stile, a marginal strip extending along the inner margin of the stile and secured thereto for shiftable movement toward and away from the main body of the stile, a row of connecting means extending through the plates into said strip, a metal channel extending along the outer margin of each stile embracing said margin and having side walls grippingly engaging the metal plate on opposite sides of the stile covering the row of connecting means adjacent to said margin of the stile, a second metal channel extending along the inner margin of each stile embracing the same and having side walls grippingly engaging the metal plates on opposite sides of the stile covering the row of connecting means extending through the plate into the strip and extending therebeyond.

20. A metal clad door comprising, in combination, a wood frame for the door, metal sheets covering the wood frame on opposite sides of the door, metal channels extending over the outer margins of the door grippingly engaging the metal sheets on opposite sides of the door, said wood frame including a wood frame member formed of two separate sections and secured together by means permitting the shifting of one section toward and away from the other section, those portions of the metal sheets covering opposite sides of said wood frame member being secured along one margin to one section thereof and secured along the opposite margin to the other section thereof.
